UNITED STATES PATENT OFFICE

CLARENCE ZENO SMITH, OF ATLANTA, GEORGIA.

PIN-REMOVER.

1,019,195.

Specification of Letters Patent. Patented Mar. 5, 1912.

Application filed January 19, 1911. Serial No. 603,571.

To all whom it may concern:

Be it known that I, CLARENCE Z. SMITH, a citizen of the United States, and resident of Atlanta, county of Fulton, State of Georgia, have invented certain new and useful Improvements in Pin-Removers, of which the following is a specification.

This invention relates to tools and has reference to that class of tools known as pin removers.

The primary object of the invention is the provision of a tool particularly adapted for removing cotter pins from the parts of machinery, and particularly from relatively light valve shafts on the motors of vehicles, without danger of distorting the shafts.

Another object is the provision of a tool which may be operated to remove a cotter pin or analogous device while in various positions with respect to the pin.

A further object is the provision of a tool adapted to spread and clench the limbs of the cotter pin after the latter has been seated.

A still further object is the provision of a tool which is adapted to engage a clenched cotter pin and draw the same through its seat without the usual necessity of first bending the limbs of the pin parallel to each other.

These and other objects will be better understood from the following description taken in connection with the accompanying drawings, in which:

Fig. 1 is a side elevation of the device showing it applied in one position to remove a cotter pin. Fig. 2 is a similar view partly in section. Fig. 3 is a detail of one of the bearing members positioned to initially spread the limbs of the pin. Fig. 4 is a detail of the other bearing member positioned to further increase the spreading of the limbs of the cotter pin preparatory to clenching the same. Fig. 5 is an end elevation of the device showing the same positioned to clench a limb of the cotter pin. Fig. 6 is a detail side elevation of the bearing end portion of the device showing it applied as in Fig. 1 but in a position at right angles to that shown in Fig. 1.

The tool comprises handle members *a* and *b*, a draw-bar or extracting member *c*, bearing members *d* and *e* and a pawl *f* for actuating the draw-bar or extracting member.

These parts are so positioned with respect to each other, that the draw-bar or extracting

element will be moved endwise when the handles are pressed, whereby an object engaged by one end of the draw-bar or extracting element will be moved therewith.

The handle *b* is made preferably of a single piece of channeled steel, and comprises a shank or gripping portion *5*, and a bearing portion *6*. Formed with or otherwise secured to an offset *7* on the inner side of the handle *b* is one end of a bearing member *8*, which corresponds in length to the bearing member *6* and extends parallel to the latter and overlies the inner surface thereof. The free end of the bearing member *8* is sharpened as shown at *9*, for a purpose to be described later.

The handle member *a* is preferably of channeled steel or its equivalent and at one end is bifurcated to provide ears *10* and *11* which bear on the opposite faces of the offset *7*. The ears *10* and *11* have alining openings which register with a transverse opening in the offset *7*, these openings receiving a pivot pin *12* which may be secured in any preferred manner such as by nuts *13*.

The draw-bar or extracting member *c* slides in the handle *b* and between the bearing members *6* and *8*, the said member *c* being recessed transversely on one side and adjacent to its outer end as shown at *15*, the outer side of said recess comprising an engaging nose or hook *16*. The opposite end of the member *c* terminates in an inwardly extending finger piece *17* which provides a finger-hold when the member is to be moved in one direction. That portion of the inner surface of the member *c* between its middle and the finger-hold *17* is provided with a plurality of ratchet teeth *18*.

The pawl *f* has one end pivoted between the sides of the handle member *a* at a point adjacent to the pivot pin *12*. This pawl is pressed by a spring *19* carried by the handle *a*, so that its free or engaging end will engage with the ratchet teeth *18*.

With this construction it will be manifest that when the parts are positioned as shown in Figs. 1 and 2, by pressing the handles *a* and *b*, the latter will turn on their pivot *12* and at the same time the pawl *f* will engage one of the teeth *18* and move the member *c* between the bearing members *6* and *8*. When pressure on the handles is released the handles will move outwardly under the action of the spring *19*, the pawl overriding the teeth *18*, whereby the parts will be posi-

tioned, when pressure is again applied thereto, to move the member *c* in the manner just described. It will be further observed that with this construction a step by step movement will be imparted to the member *c*. In order to yieldingly hold the member *c* against movement opposite to the movement imparted thereto by the pawl *f*, and during the time the latter is sliding over the teeth 18, a spring 23 is employed. One end of this element is secured to the offset 7 and the opposite end curves inwardly and normally bears on the adjacent surface of the member *c*.

15 In use, and assuming the parts are positioned as shown in Fig. 2, the pawl *f* is raised from engagement with the teeth 18 and the engaging end of the member *c* is moved outwardly and beyond the extremities of the bearing members 6 and 8 by pressing on the portion 17. The nose 16 is then inserted through the eye 20 of the cotter pin and the handles operated in the manner before described, until the extremities of the bearing members 6 and 8 bear on the object retained by the pin, as shown in Fig. 1, whereupon continued movement of the handles *a* and *b* will further move the draw-bar to pull the pin from its seat.

20 Inasmuch as the material of which most cotter pins are made is comparatively light, and the leverage produced on the member *c* is comparatively great, it will be seen that during the inward movement of the handles, the pin will be readily drawn through its seat even though the limbs 21 and 22 thereof are spread apart or clenched, as shown in Fig. 5, whereby the usual necessity of first bending the limbs parallel 25 to each other, will be avoided.

25 In Fig. 1 the parts are shown positioned to remove the pin with the draw-bar or extracting element in alinement therewith. It frequently happens, however, that cotter pins are assembled with parts arranged in spaces whose width is less than the length of the tool. I have found with the present construction that the tool will operate equally as well when in a position at right angles to the pin as shown in Fig. 6, as when alining with the pin as shown in Fig. 1. When the tool is to be used as shown in Fig. 6, the part 16 is engaged as before described and the tool turned to a position 30 at right angles to the pin or until the bearing members 6 and 8 get a suitable purchase on the nut, shank, or other object as the case may be, whereupon the movement of the member *c* in the manner before described 35 will remove the pin from its seat.

40 In Fig. 3 I have shown the bearing member 8 initially spreading the limbs 21 and 22 of the pin after the latter has been seated. Owing to the shape of the end 9, the limbs 45 21 and 22 will be considerably spread when

the member 8 has been forced therebetween. In order to effect further spreading the bearing member 6 is inserted between the limbs, as shown in Fig. 4, whereupon the limbs will be spread to the position shown 70 in Fig. 5. In order to clench the limbs, whenever desired, the limbs are alternately inserted through the recess 15, as shown in Fig. 5, and bent outwardly and around the object.

Having thus described the invention, what is claimed is:

1. The herein described implement for withdrawing cotter pins comprising a body having at one end spaced bearing members, 80 adapted to receive between them the head of a cotter pin, and having its other end forming a handle, a second handle member pivotally connected at one end with the body, a draw bar supported by the body 85 to move between the bearing members thereof and provided at its end that moves between said members with means to engage the head of a cotter pin, said bar having a series of teeth arranged on the opposite 90 side of the axis of the pivot of the second handle member from said pin engaging means, and a feed pawl attached to the pivoted handle member and engaging said teeth.

2. The herein described implement for withdrawing cotter pins comprising a body formed with a longitudinally extending groove or channel that extends through one end thereof, a handle member pivotally connected at one end with the body and extending rearwardly over said groove, a toothed draw bar supported in the groove in the body and having at one end means for engaging the head of a cotter pin, and 100 a feed pawl connected to the pivotally mounted handle member and engaging the teeth of the draw bar.

3. The herein described implement for withdrawing cotter pins comprising an 110 elongated body, one end of which is adapted to be placed in contact with the article from which the pin is to be withdrawn, a toothed draw bar of less length than the body supported by the latter to move longitudinally thereof and provided at one end with means for engaging with the head of a cotter pin, and a handle member pivotally connected at one end with the body 115 and provided at an intermediate point in its length with a pawl that engages the teeth of the draw bar.

4. The herein described implement for withdrawing cotter pins comprising a body having one end bifurcated to form two 125 bearing members adapted to receive between them the head of a cotter pin, one of said bearing members being tapered toward its free end, whereby it may be utilized to spread the limbs of a cotter pin, a toothed 130

draw bar supported by the body to move between said bearing members and provided with means for engaging the head of a cotter pin inserted between said members, 5 and a handle member pivotally connected with the body and provided with a pawl that engages the teeth on the draw bar.

5. The herein described implement for withdrawing cotter pins comprising two 10 members, one having one end pivotally connected with ears that project laterally from the other member at an intermediate point in its length, a toothed draw bar supported by one of said members and provided at 15 one end with means for engaging the head of a cotter pin, and a feed pawl connected with the other said member and engaging the teeth of the draw bar, whereby said bar may be moved longitudinally by rocking 20 the pivotally mounted member about its fulcrum.

6. The herein described implement for withdrawing cotter pins comprising two channeled or longitudinally grooved members of different lengths, one having at an 25 intermediate point in its length laterally projecting ears to which one end of the other said member is pivoted, a toothed draw bar supported in the groove in the longer of said members and extending in 30 advance and rear of the said ears, said bar being adapted to engage the head of a cotter pin, and a pawl pivotally supported in the groove in the other said member and engaging the teeth on the draw bar. 35

In testimony whereof I affix my signature in presence of two witnesses.

CLARENCE ZENO SMITH.
